UNITED STATES PATENT OFFICE.

HARVEY W. BLAUCH, OF PALMYRA, PENNSYLVANIA.

RAILROAD-TIE.

SPECIFICATION forming part of Letters Patent No. 645,062, dated March 13, 1900.

Application filed December 12, 1899. Serial No. 740,088. (No. model.)

To all whom it may concern:

Be it known that I, HARVEY W. BLAUCH, a citizen of the United States, residing at Palmyra, in the county of Lebanon and State 5 of Pennsylvania, have invented a new and useful Railroad-Tie, of which the following is a specification.

This invention relates to railway-ties in general, and more particularly to metallic ties; and it has for one object to provide a construction to which the rails may be easily connected and firmly held, a further object being to provide a structure in which the separation of the rails may be varied and to 15 which a guard-rail may be attached for each of the track-rails, the structure of the ties being such as to preclude the necessity of the usual care in tamping differently at different points in the length of the tie.

Figure 1 is a perspective view showing a tie having portions of rails connected therewith. Fig. 2 is a central section of the tie, taken transversely of the rails. Fig. 3 is a transverse section of one portion of the tie 25 and showing a rail and the attaching-bolt in elevation. Fig. 4 is a view similar to Fig. 2 and showing a different form of rail-clamping plate. Fig. 5 is a view similar to Figs. 2 and 4 and showing a tie with curved track-rails 30 and guard-rails fixed thereon.

Referring now to the drawings, the tie of the present invention comprises two parts 10 and 11, which are similar in every respect and which parts each comprise a bottom 35 plate 12, having its edges turned upwardly to form sides 13 and 14, between which sides and bottom are fixed end blocks 15. A covering-plate 16 is disposed upon the upper edges of the sides 13 and 14 and the ends 15, 40 and this covering-plate has its side edges bent downwardly to lie upon the outer faces of the sides 13 and 14 and to which they are riveted. The outer ends of the sections 10 and 11 are provided with covers 17, provided with ears 45 18, through the medium of which the covers are hinged to the downturned edges of the covering-plates 16. By this means access to the interior of the tie-section may be had at all times, and the ends of the tie-sections may 50 be closed to prevent the ballast entering the sections,

In the cover-plate 16 of each tie-section are formed perforations through which are passed clamping-bolts 19, which engage clamping-plates 20 and 21. A plate 20 and a plate 21 55 are connected with each of the tie-sections and are disposed out of alignment transversely of the trackway and have their under faces at their mutually-adjacent ends beveled to lie upon the flange of the track-rail 23 to hold the 60 rail upon the tie-section.

In order to hold the tie-sections against displacement with respect to each other, the end blocks 15 are perforated centrally, and these 65 perforations are threaded and are adapted for alignment. The thread of the perforation of one end block is a right-hand thread, while the perforation of the corresponding block has a left-hand thread, and with the threads of these perforations are engaged the threaded 70 ends of a right and left threaded adjusting-bar 25, having a central angular portion 26, adapted to receive a wrench. Jam-nuts 27 are disposed upon the adjusting-bar, so that after the tie-sections have been properly positioned they may be held against displacement. 75

From the above construction it will be seen that by manipulation of the adjusting-bar the tie-sections may be moved toward or away 80 from each other to assume the proper correlative positions and that the rails will be rigidly held in place.

To permit application of the nuts to the lower ends of the bolts 19, openings 29 are 85 made in the sides of the tie-sections and are of sufficient size to permit the insertion of the hand of the operator, these openings having closures 30. Plates 37 in the form of webs are disposed vertically and longitudinally of 90 each of the tie-sections and are so positioned that the nuts upon the clamping-bolts will lie against them to permit clamping action by manipulation of the bolts from the heads of the latter. 95

It will be seen that by making the tie in two parts a large percentage of the metal of the usual tie is saved, simple and efficient means for adjusting the positions of the rails is provided, and at the same time the tie-sections may be tamped to the same extent 100 throughout their lengths, thus eliminating

the care usually required in graduating the tamping from the ends toward the middle of the tie.

In Fig. 4 of the drawings there is shown a construction similar to that just described and employing a different form of clamping-plate 30^a, the base of which is extended, as shown, to receive two clamping-bolts 31^a, this structure being employed where the tendency to spreading of the rails is above normal.

In Fig. 5 of the drawings the tie is shown as adapted for the reception of the track-rails and the guard-rails at a curve, the track-rails 32 and guard-rails 33 having common clamping-plates 34, one of which is disposed between the track-rail and guard-rail upon each tie-section, and each of the track-rails having an exterior clamping-plate 35, while each of the guard-rails has a corresponding clamping-plate 36. In this embodiment of the invention plates 37 are employed to lie against the nuts of the clamping-bolts 38 to prevent their rotation.

It will of course be understood that in practice the several parts of the tie-sections may be cast or formed of sheet metal and that the particular outlines and the dimensions thereof may be varied without departing from the spirit of the invention.

30 What is claimed is—

1. A railway-tie comprising a hollow supporting portion, openings in the supporting portion, clamping-plates having bolts passed therethrough and into the openings, nuts upon the inner ends of the bolts, and additional plates within the hollow supporting portion and lying against the faces of the nuts, said plates being attached to the top and the bottom of the hollow supporting portion to support the top.

40 2. A railway-tie comprising a plurality of

hollow sections adapted to receive rails, means for adjusting the sections, each of said sections comprising a bottom and sides formed integral, a cover-plate fixed to the edges of the side and end blocks at one end of the body portion, means connected with the end blocks for adjusting the body portions toward and away from each other, and a cover hinged to the outer end of each body portion to permit access thereto at times and to prevent ingress of ballast when the bodies are adjusted.

3. A railway-tie comprising a hollow supporting portion, openings in the supporting portion, clamping-plates having bolts passed therethrough and into the openings, nuts upon the inner ends of the bolts, and plates within the hollow bearing portion and lying against flat faces of the nuts.

4. In a railway-tie, the combination with a hollow body portion having openings therein, of a clamping-plate having openings alining with the openings of the body portion, clamping-bolts passed through the alining openings and having nuts at their inner ends, hand-holes in the body portion, and means for engagement with the nuts to hold them from rotation.

5. A hollow tie comprising a bottom and sides formed integral, a cover-plate fixed to the edges of the sides, an end block at one end of the body portion, and a cover hinged to the opposite end of the body portion to close the tie.

In testimony that I claim the foregoing as my own I have hereto affixed my signature in the presence of two witnesses.

HARVEY W. BLAUCH.
